ADJUSTABLE HOLDING DEVICE

Original Filed May 27, 1927

UNITED STATES PATENT OFFICE

FLOYD M. WILLIAMSON, OF DETROIT, MICHIGAN

ADJUSTABLE HOLDING DEVICE

Application filed May 27, 1927, Serial No. 194,569. Renewed August 12, 1929.

This invention relates to improvements in adjustable holding devices, and refers more particularly to holding devices for holding the outer ends of pivotally connected members at varying distances from fixed members, or for holding the outer ends of two members pivotally connected to one another at varying distances apart.

It is an object of the invention to provide an adjustable holding device which can be quickly and easily set so as to maintain a pivotally mounted member at varying distances from a fixed member on which it is mounted, either when the outer margins of the said members are substantially in the same plane and adjacent to one another, or when the pivotal member is swung away from the fixed member and has its outer margin inclined at an angle to the margin of the fixed member.

Another object of the invention is to provide an adjustable holding device which can be cheaply and easily made and applied.

Having thus outlined the major purposes of the invention I will now proceed to describe an embodiment thereof with the aid of the accompanying drawings, in which:

Figure 1 illustrates a perspective view of the invention with the upper margin of the pivotal member inclined at an angle to the fixed member, and

Figure 2 is an end view of Figure 1.

Figure 3 shows a plan view of the invention, and

Figure 4 is a side view thereof.

Figures 5 and 6 are sections on the lines 5-5 and 6-6 of Figure 3. Figures 7 and 8 are details of the arm and slide.

Referring to the drawings, 1 designates a window pivotally mounted at 2 in a window frame 3. On the latter an angle plate 4, having a substantially horizontal upper surface 5, is provided. The said upper surface has an opening 6 therethrough to receive the downturned end 7 of an arm 8, the opposite end of which latter has an aperture 9 therethrough.

On the upper margin 10 of the window 1 a guide plate 11 is secured. This guide plate 50 has a longitudinal raised bearing sur-

face 12 through which an elongated slot 13 is cut. The outer margin of the bearing surface portion 12^a adjacent to the window frame 3 is longitudinally substantially parallel with the underside of the guide plate, whereas the outer margin of the bearing surface portion 12^b remote from the window frame 3 is upwardly inclined from the end A of the guide plate to its end B; that is upwardly inclined towards the end of the bearing surface directly opposite the plate 4. It will also be noted that the bearing surface portions 12^a and 12^b are substantially parallel with one another transversely throughout their length, and are gradually at a lesser angle to the underside of the guide plate from the end B of the latter until they are substantially parallel with the underside of the said guide plate at its end A.

A slide 14 is provided under the bearing surface which is wider than the slot 13, and has an upwardly projecting pin 15 thereon which passes through the said slot. Moreover it will be noted that the pin is preferably provided with a flat side 15^a thereon which bears against one side of the slot 13 so that the slide is positively held against rotation. The upper portion of the pin is threaded, passes through the aperture 9 in the arm 8, and has a nut 16 in threaded engagement with it, so that by tightening the nut the arm is clamped between it and the bearing surface 12.

It is of course obvious that the angle of incline of the outer bearing surface portion 12^b longitudinally must be made to suit the length of the window 1 from its pivotal point 2 to its upper margin 10, since one object of the invention is to provide a guide plate having a bearing surface so formed as to compensate for the varying angularity between the upper surface 5 of the plate 4 and the margin 10 of the window 1 as the latter moves pivotally, since the outer end of the arm 8 is always at the same location along the bearing surface when the pivotally mounted window is swung outwards a given distance, and is inclined at a given angle.

While in the foregoing the preferred embodiment of the invention has been described

and shown, it is understood that the construction is susceptible to such modifications as fall within the scope of the appended claims.

What I claim as my invention and desire to secure by Letters Patent is:

1. A device of the character described comprising a guide having a longitudinal raised bearing surface, said bearing surface having an elongated slot therethrough, the bearing surface on one side of said slot having its outer margin substantially parallel with the underside of the guide and the bearing surface on the other side of the slot having its outer margin upwardly inclined from one end, and an arm having one end adapted to be pivotally mounted and its opposite end extending over said slot, in combination with means extending through said slot for holding said opposite end of said arm against said bearing surface at any location therealong.
2. A device of the character described comprising a guide having a longitudinal bearing surface, said bearing surface having an elongated slot therethrough, the bearing surface on one side of said slot having its outer margin substantially parallel with the guide, and the bearing surface on the other side of the slot having its outer margin upwardly inclined from one end, said bearing surface portions being substantially parallel with one another transversely throughout their length, and an arm having one end adapted to be pivotally mounted and its opposite end extending over said slot, in combination with a slide movable under said bearing surface, and means for pivotally connecting said arm with said slide.
3. A device of the character described comprising a guide having a longitudinal bearing surface, said bearing surface having an elongated slot therethrough, the bearing surface on one side of said slot having its outer margin substantially parallel with the guide, and the bearing surface on the other side of said slot having its outer margin upwardly inclined from one end, said bearing surface portions being substantially parallel with one another transversely throughout their length, and an arm having one end adapted to be pivotally mounted and its opposite end extending over said slot, in combination with means for holding said opposite end of said arm against said bearing surface at any location therealong, said means extending through said slot.
4. In a closure fastener, an arm adapted to be pivotally secured at one end to the frame of a closure, a guide device adapted to be carried by a closure and having a slot therein and a relatively wide bearing surface on either side of the slot and upon which the rod is adapted to ride, a fastening device on the rod engaging in the slot to hold a closure in a predetermined position with respect to

its frame, and the guide being formed to dispose the bearing surface at an incline approximating the angular position of the rod with respect to the guide to present the maximum surface of the guide to contact with the rod irrespective of the relative position of the closure to its frame.
